DECARBONIZER FOR COKE OVENS

Maurice D. Curran, Glendale, Mo., assignor to
Tar & Petroleum Process Company, Chicago,
Ill., a corporation of Illinois

Application August 8, 1938, Serial No. 223,592

1 Claim. (Cl. 202—241)

The present invention relates to improvements in decarbonizers for coke ovens.

The present invention has particular reference to the flat type of oven in which the coking chamber is relatively shallow compared to the length and the width thereof. This type of oven is known commonly in the art as the Knowles type of oven and is illustrated in the Knowles and McIntyre Patent No. 1,635,280. In the operation of such an oven the coal which is to be coked is charged into the oven and leveled off, and, after the coking operation has been carried to the point desired, the charge is pushed out of the oven. During the coking operation there is a tendency toward the gradual accumulation of hard carbon, which adheres to the oven floor. This carbon is insulating in its effect and therefore objectionable. In the absence of means for removing this carbon it is necessary to shut the oven down periodically and to remove the carbon either by combustion or by chipping. Though the present invention is particularly applicable to ovens of the Knowles type and has been illustrated in connection with that type of oven, it will be understood as the description proceeds that the invention is of broader application.

An object of the present invention is to provide means for removing the accumulation of carbon tending to adhere to the floor or other wall of a coking oven during each coking operation, this removal being accomplished during the step of pushing the charge from the oven.

A further object is to provide mechanism for burning out such accumulated carbon which in its operation requires no shutting down of the oven and no interruptions to the normal operation of the oven.

A further object is to provide improved means for removing the accumulation of carbon from a coking oven, which means are well adapted to meet the needs of commercial operation.

Further objects will appear as the description proceeds.

Referring to the drawings—

Figure 1 is a view, partly in section, showing a commercial adaptation of the present invention;

Figure 2 is a view showing part of the mechanism illustrated in Figure 1 but on a larger scale and better illustrating the mechanism embodying the present invention;

Figure 3 is a detail plan view showing certain features of the present invention;

Figure 4 is a sectional view taken along the plane indicated by the arrows 4—4 of Figure 3;

Figure 5 is a perspective view illustrating the

leveler ram assembly, the pusher ram assembly, and certain mechanism which may be utilized for connecting the pusher ram assembly to or disconnecting it from the leveler ram assembly; and

5 Figure 6 is a fragmentary view illustrating a very simple means for connecting the pusher ram assembly to or disconnecting it from the leveler ram assembly.

The numeral 10 indicates as a whole an oven 10 of the Knowles type. Said oven has projecting from the two ends thereof the platforms 11—11, which have their upper surfaces at substantially the level of the floor of the oven. The numeral 12 indicates as a whole a pusher and leveler assembly mounted on wheels 13—13 and adapted to travel along the tracks 14—14, whereby the pusher and leveler assembly may travel along a battery of ovens and operate upon the various ovens thereof in succession. Said pusher and leveler assembly is provided with a leveler ram, indicated by the numeral 15, which leveler ram includes a pair of longitudinal members 16 carrying at their forward extremity the leveler head 17. The leveler ram 15 may be moved longitudinally, that is, into and out of the oven 10, by means of a cable 18 attached to said leveler ram and wound around a pair of sheaves 19—19 located adjacent to the ends of the pusher and leveler assembly 12. Said cable 18 may be operated by a sheave 20 driven from a pulley 21, which may be driven by any preferred motive mechanism. Associated with the leveler ram 15 is the pusher ram 22, including the longitudinally extending channels 22a—22a and provided at its forward extremity 23 with the pusher head 23. The leveler head 17 is provided with the feet 24 adapted to ride upon a platform 25 forming part of the pusher and leveler assembly 12 and upon the platform 11 and the oven floor of the oven 10. Figures 1 and 2 show the leveler ram 15 and the pusher ram 22 in their fully retracted positions. In this position the forward extremity of the pusher ram 22 rides upon the platform 25. The leveler ram 15 may be supported and guided by rollers, not shown. Said pusher ram 22 is adapted to be connected to and disconnected from the leveler ram 15 through mechanism which need not be described in detail herein inasmuch as the specific mechanism does not constitute the present invention. It may be explained briefly that the rearward extremity of the pusher ram 22 is provided with the upwardly extending portion 27 adapted to hook over a portion of the leveler ram 15, whereby said pusher ram 22 will be reciprocated longitudinally with the reciprocations of the

pusher ram 15. A manually operable lever 28 is provided for raising said rear extremity of the pusher ram 22 when it is desired to connect said pusher ram 22 to or disconnect said pusher ram from the leveler ram 15. Said lever 28 is illustrated in its lowered position, to which position it is moved after it has been operated to raise the rear extremity of the pusher ram 22 into position to interlock with the leveler ram 15.

Figure 5 illustrates in a perspective view mechanism which may be utilized for lifting the rear extremity of the pusher bar assembly whereby it may be connected to the leveler bar assembly. Disposed upon the inner faces of the longitudinal members 16-18 are the cam plates 28a-28a, each provided with the cam slot 28b. Said cam slots are adapted to cooperate with transversely extending pins 28c extending laterally from the channels 22a-22a of the pusher ram 22. The rear extremity of the pusher ram 22 may be raised or lowered by means of the manually operable lever 28 whereby the laterally extending pins 28c-28c may be engaged in the cam slots 28b-28b or may be disengaged from said cam slots 28b-28b.

Figure 6 illustrates a very simple construction in which pins 28d-28d may be utilized to connect each channel 22a with the corresponding longitudinal member 16 by means of its engagement with cooperating holes 28e-28e in said members 16 and 22a.

United to the pusher ram 22 a short distance in the rear of the pusher head 23 is the burner pipe 29. Said burner comprises a pipe mounted in parallel relationship with the pusher head 23. Said pipe 29 is provided with a plurality of orifices 30-30 disposed in a line adjacent to the bottom of said pipe 29, whereby air for combustion purposes may be delivered against the floor of the oven to burn off carbon which has collected upon said floor. Said pipe 29 is secured to the channels 22a-22a, which form part of the pusher ram 22. As shown in Figure 4, the lower sides of the channel members 22a-22a are set into cut-out portions of the pipe 29, welding material, indicated by the numeral 31, being disposed in place to prevent leakage from the pipe 29 through said cut-out portions. The ends of the pipes 29-29 will, of course, be closed. Connected to the mid region of said pipe 29 is the air supply conduit 32, which extends rearwardly from said pipe 29. Said conduit 32 will be supported from the pusher ram 22 by any preferred means. Said conduit 32 extends to a region spaced a short distance in the rear of the rear extremity of the pusher ram 22, and at that region is connected to a flexible joint 33, which flexible joint is connected to the elongated conduit 34, which extends back to the region adjacent to the rear of the pusher and leveler assembly 12. The rear extremity of said conduit 34 is connected to the flexible conduit 35, which at its other extremity is connected to the source of compressed air 36.

Rotatably carried by the leveler ram 15 is the longitudinally extending rod 37 adapted to be

rocked by the lever 38. Said longitudinally extending rod 37 is provided with a plurality of hook members 39 spaced therealong adapted to pick up the elongated conduit 34 and carry it along with the leveler ram 15. A plurality of brackets 40-40 are provided upon which the elongated conduit 34 lies when said elongated conduit 34 and the conduit 32 are disconnected from the leveler ram 15.

The mode of operation of the above described embodiment of the present invention is substantially as follows:

When it is desired to use the leveler ram 15 in leveling off the charge within the oven 10, the rear extremity 27 of the pusher ram 32 will be released from the leveler ram 15 and the conduit 34 will lie upon the brackets 40-40. At this time the leveler ram may be operated independently of the pusher ram 22 and will perform its function of leveling off the charge within the oven 10.

When the coking operation has been carried on within the oven 10 to the point desired and it is desired to push the charge from the oven, the lever 28 will be operated to raise the rear extremity 27 of the pusher ram 22 up into position to interlock with the leveler ram 15. Also, the lever 38 will be operated to turn the longitudinally extending rod 37 to cause the hooks 39-39 to lift the elongated conduit 34 from the brackets 40-40. Operation of the sheave 20 will cause longitudinal movement of the leveler ram 15 and the pusher ram 22 as a unit, carrying the conduits 32 and 34 along therewith. Air under pressure will be admitted to the flexible conduit 35, and said air will pass by way of the conduits 34 and 32 to the burner pipe 29 to be delivered through the orifices 30-30. Inasmuch as the oven is at high temperature, the delivery of the air through the orifices 30-30 will cause the combustion of any layer of carbon adhering to the floor of the furnace behind the pusher head 23. Accordingly, any layer of carbon tending to remain behind the pusher head will be burned off in the same operation which results in the pushing of the charge from the oven. Furthermore, particles on the floor of the oven not consumed by such combustion will be swept from said floor by the flow of air from said orifices 30-30.

Though a preferred embodiment of the present invention has been described in detail, many modifications will occur to those skilled in the art. It is intended to cover all such modifications that fall within the scope of the appended claim.

What is claimed is:

A combined pushing and leveling device for use with coke ovens comprising a leveling bar assembly, means for moving said assembly, a pusher bar assembly arranged to be connected to said leveling bar assembly to operate in unison with said leveling bar assembly but being separable from said leveling bar assembly, and air delivery means connected to move with said pusher bar assembly.

MAURICE D. CURRAN.
